UNITED STATES PATENT OFFICE

162,337

SACROILIAC BAR

James A. O'Gatty, Los Angeles, Calif.

Application March 17, 1950, Serial No. 8,578

Term of patent 14 years

(Cl. D83—1)

To all whom it may concern:

Be it known that I, James A. O'Gatty, a citizen of the United States, residing at Hollywood, in the county of Los Angeles and State of California, have invented a new, original, and ornamental Design for a Sacroiliac Bar, of which the following is a specification, reference being had to the accompanying drawing, forming part thereof.

Fig. 1 is a perspective view of a sacroiliac bar, embodying my new design.

Fig. 2 is an enlarged perspective view of the bracket on the left in Fig. 1; and

Fig. 3 is an enlarged perspective view of the bracket on the right in Fig. 1.

The sides of each end bracket opposite to those shown in the drawing are substantially plain.

I claim:

The ornamental design for a sacroiliac bar, as shown and described.

JAMES A. O'GATTY.
